UNITED STATES PATENT-OFFICE.

HAROLD JARVIS, OF BUFFALO, NEW YORK, ASSIGNOR TO JARVIS TYPE-WRITER & TABULATOR COMPANY, OF BUFFALO, NEW YORK.

TYPE-WRITING MACHINE.

SPECIFICATION forming part of Letters Patent No. 699,389, dated May 6, 1902.

Application filed July 2, 1901. Serial No. 66,860. (No model.)

To all whom it may concern:

Be it known that I, HAROLD JARVIS, a citizen of the United States, residing at Buffalo, in the county of Erie and State of New York, 5 have invented new and useful Improvements in Type-Writing Machines, of which the following is a specification.

This invention relates to type-writing machines having in addition to the ordinary unit 10 form feed or spacing mechanism for the paper-carriage a supplemental variable spacing mechanism which enables the carriage to skip a predetermined number of single spaces for tabulating purposes or for printing words or 15 phrases as well as single-space characters. Machines of this kind are shown and described in Letters Patent of the United States, No. 536,588, granted to me March 26, 1895, and in an application for patent filed by H. M. 20 Blakeslee and myself on the 1st day of February, 1901, Serial No. 45,625, to which patent and application reference is made for a full description of the variable feed and controlling devices of the paper-carriage. When the carriage skips a number of spaces and is suddenly 25 arrested by a rigid stop, the impact jars and strains the parts of the machine with greater or less severity, according to the distance that the carriage travels before being stopped. To 30 diminish the force of this shock, I have heretofore devised an automatic governor which operates to check or retard the speed of the carriage under the impulse of its feed-spring when the carriage is released from its escapement or feed mechanism. This governor is 35 described in the application for patent above referred to.

The object of my present invention is the provision of a simple and effective governor 40 or retarder for the carriage which is easily applicable to a typewriting or tabulating machine and which is so located as not to interfere with other parts of the machine or require a rearrangement of the same.

45 In the accompanying drawings, consisting of two sheets, Figure 1 is a top plan view of a type-writing machine with a tabulator attachment provided with my improved governor. Fig. 2 is a detached rear view of the 50 governor. Fig. 3 is a vertical longitudinal section of the machine in line 33, Fig. 1. Fig.

4 is a fragmentary transverse vertical section in line 44, Fig. 1. Fig. 5 is a fragmentary front view of the gear-rack of the paper-carriage, its escapement-pinion, and parts of the 55 governor. Fig. 6 is a vertical longitudinal section of the governor mechanism in line 66, Fig. 1.

A is the frame of the machine, B the rear portion of the customary paper-carriage, and 60 B' its vertically-swinging front portion, which carries the platen b.

The carriage is actuated by the usual spring-drum, which is not shown in the drawings, and controlled by an escapement or uniform 65 feed mechanism of any suitable or well-known construction. In the construction shown in the drawings the feed mechanism consists of a longitudinal shaft c, journaled on the top frame of the machine and provided at its 70 rear end with a ratchet or escapement wheel c' and at its front end with a pinion c², which meshes with a transverse gear-rack c³, mounted on the carriage and capable of swinging or otherwise moving vertically thereon. The 75 movement of the usual main keys D is transmitted to the escapement-wheel c' by any ordinary or suitable mechanism, which is not shown in the drawings inasmuch as it forms no part of my invention. The devices for effecting the necessary variable travel of the carriage for tabulating purposes also form no part of my present invention and may be of any suitable or approved construction—for instance, like that shown and described in 80 my pending application for patent hereinbefore referred to. My improved governor is herein shown as applied to the tabulator attachment of said pending application, and to better enable those skilled in the art to understand its relation to the tabulator the description of the governor will be prefaced by a brief description of those parts of the tabulator with which the governor co-operates.

The tabulator attachment comprises lifting 95 devices for raising the gear-rack c³ of the carriage out of engagement with the escapement-pinion c², a series of auxiliary push-keys for actuating said lifting devices, an automatic lock for holding the gear-rack in its inoperative position during the travel of the carriage, and automatic stop and trip devices for re-

leasing said lock and allowing the gear-rack to return into engagement with the escapement-pinion c^2 .

Referring to Figs. 1 and 3, E represents the auxiliary push-keys, mounted on the front end of horizontal rods e , which extend from the front to the rear end of the machine and engage with the lower arms of vertical bell-crank levers e' . These levers actuate an elbow-shaped universal frame F, which preferably swings upon the same fulcrum as said levers. The lower rod f of this frame extends across the rear side of the series of bell-crank levers e' , so that upon pushing any one of the auxiliary keys E the universal frame is actuated through the medium of the corresponding bell-crank lever.

G, Fig. 1, is a vertically-movable frame or support arranged at the top of the machine, preferably in rear of the usual type-bar basket, and composed of two parallel arms g , arranged transversely of the machine and connected at their front ends by a rod g' and secured at their rear ends to opposite ends of a rod g^2 , which rocks in a bearing g^3 , mounted on the top frame of the machine. The free end of the frame G is raised by a vertically-swinging arm H, which engages under the adjacent rod g' of said frame and which in turn is elevated by a lever H' , having its outer arm connected with the upper rod f' of the universal frame F, so that upon rocking this universal frame by the depression of an auxiliary key E the frame G is raised through the lever H' and the arm H. This arm H and the lever H' are pivoted to swing vertically on the top frame of the machine, and the lever is provided with a lateral pin h , which engages under the arm, as shown in Figs. 1 and 4.

I is a driving-shaft carried by the vertically-movable frame G and preferably journaled in a comparatively long bearing i , mounted on said frame, as shown in Figs. 1, 4, and 6. This shaft extends fore and aft of the machine and is provided at its front end with a pinion j , which meshes with the gear-rack c^3 of the paper-carriage, as seen in Figs. 5 and 6. By this construction the shaft I is geared with the paper-carriage and rotated by the movement thereof, and the gear-rack of the carriage is lifted out of engagement with its escapement-pinion c^2 by said shaft and the pinion j upon operating one of the auxiliary keys E.

k is a governor-shaft, preferably arranged above the plane of the driving-shaft I and parallel therewith. This governor-shaft is supported in a bearing or standard L, rising from the adjacent portion of the frame of the machine, and is provided at its front end with a pinion k' , which is arranged to mesh with a gear-wheel m , secured to the rear end of the shaft I when the latter is in its elevated position, as shown in Fig. 6, and to clear said pinion when said shaft is in its lowered position, as shown in Fig. 4. The governor-shaft k is

provided at its rear end with pivoted arms n , carrying governor weights or balls n' , which move outward by centrifugal force. The governor-arms n are arranged in a rearwardly-flaring cavity or socket n^2 , formed in the rear side of the standard L and impinge against the surrounding wall of said socket when thrown outward by centrifugal force. The arms thus act as a friction-brake, which retards the rotation of the governor-shaft k and its driving-shaft I, causing the latter in turn to retard the speed of the paper-carriage through the medium of the pinion j and the gear-rack c^3 .

The driving-shaft I and its carrying-frame G assume their depressed position by gravity. If desired, this movement may be aided by a spring. In the ordinary condition of the machine this driving-shaft is in its lowered position out of gear with the centrifugal governor, as shown in Fig. 4.

In the use of the tabulator upon depressing one of the auxiliary or tabulator keys E the gear-rack c^3 is lifted out of engagement with its escapement-pinion c^2 , as shown by dotted lines in Fig. 5, by the upward movement of the driving-shaft I, as hereinbefore described, and this shaft is at the same time brought into gear with the governor-shaft k , as shown in Fig. 6. The carriage is thus released and slid across the machine by the action of its customary spring; but as the automatic brake or governor is set in motion at the moment that the carriage is released it opposes the action of said spring and checks the speed of the carriage, easing the shock at the end of the carriage-stroke and relieving the machine from the wear and tear which would otherwise result.

It will be observed that although the driving-shaft I is moved into and out of gear with the governor-shaft k the driving-shaft rises and falls with the gear-rack c^3 of the paper-carriage and always remains in gear therewith.

The frame G is preferably provided with a lifting-shoe o , which engages against the under side of the gear-rack c^3 and relieves the pinion j from wear in lifting the rack.

By my improved construction and arrangement the carriage-governor or speed-retarder may be located wholly in rear of the type-bar basket, as shown, where it does not in any way interfere with the movement of the type-bars and where it can be readily applied and is convenient of access for repairs.

Although the centrifugal governor herein shown and described is a desirable one, I do not wish to be understood as limiting myself to the particular construction disclosed, as the same is susceptible of various modifications coming within the spirit of my invention.

I claim as my invention—

1. In a type-writing machine, the combination with a paper-carriage and a step-by-step feed mechanism therefor, the carriage being

- capable of disconnection from said feed mechanism, and a speed-governor comprising a governor-shaft, a driving-shaft from which said governor-shaft is driven and which is movable into and out of gear therewith, and gearing between the carriage and said driving-shaft for rotating the latter by the movement of the carriage, substantially as set forth.
- 10 2. In a type-writing machine, the combination with a paper-carriage having a gear-rack, of a speed-governor comprising a governor-shaft having a pinion, and a driving-shaft movable toward and from said governor-shaft and having gear-wheels arranged to engage with said gear-rack and the pinion of the governor-shaft, substantially as set forth.
- 15 3. In a type-writing machine, the combination with a paper-carriage, of an escapement therefor, one member of which consists of a vertically-movable gear-rack mounted on the carriage and capable of engaging and leaving the other member, a governor-shaft, a vertically-movable driving-shaft from which said 20 governor-shaft is driven and which is movable into and out of gear therewith, said driving-shaft having a pinion which engages with the toothed lower edge of said gear-rack, substantially as set forth.
- 25 30 4. In a type-writing machine, the combination with a paper-carriage and an escape-

ment therefor having a pinion, of a vertically-movable gear-rack mounted on said carriage and capable of moving into and out of gear with said pinion, and a speed-governor comprising a vertically-movable driving-shaft geared with said gear-rack and having a gear-wheel, and a governor-shaft arranged above said driving-shaft and having a pinion arranged to mesh with the gear-wheel thereof when the driving-shaft is raised, and means for elevating said driving-shaft, substantially as set forth.

5. In a type-writing machine, the combination with a paper-carriage having feed mechanism from which it can be disconnected, of a governor-shaft, a vertically-movable frame or support arranged below the plane of said governor-shaft, a driving-shaft for said governor-shaft journaled in said frame, a driving means connecting said driving-shaft with the paper-carriage, a series of auxiliary keys, and lifting devices for said vertically-movable shaft-frame which are operated by said keys, substantially as set forth.

Witness my hand this 13th day of June, 1901.

HAROLD JARVIS.
